UNITED STATES PATENT OFFICE.

THOMAS C. PETERSEN AND ERIK A. EKEDAHLL, OF JAMESTOWN, NEW YORK, ASSIGNEES TO
ART METAL CONSTRUCTION COMPANY, OF JAMESTOWN, NEW YORK, A CORPORATION
OF NEW YORK.

BOOK-SHELF.

No. 921,884.

Specification of Letters Patent.

Patented May 18, 1909.

Application filed November 2, 1908. Serial No. 460,699.

To all whom it may concern:

Be it known that we, THOMAS CARL PETERSEN and ERIK A. EKEDAHLL, residents of Jamestown, in the county of Chautauqua and State of New York, have invented a new and useful Improvement in Book-Shelves; and we do hereby declare the following to be a full, clear, and exact description thereof.

Our invention relates to roller book shelves which consists essentially in a skeleton frame 10 with anti-friction rollers arranged therein to permit of the ready insertion and withdrawal of heavy books.

The object of our invention is to provide for the construction of such shelves without the employment of rivets whereby a more accurate shelf can be formed as the hammering necessary in riveting is dispensed with and the parts are interlocked in such a manner as 20 to be readily assembled with practically no hammering, so that after the parts have been separately japanned the parts, as well as the rollers, may be readily assembled without injuring the finish.

25 To these ends our invention comprises the novel features hereinafter set forth and claimed.

In the accompanying drawings Figure 1 is a view of a case partly broken away showing 30 our improved shelf as applied thereto; Fig. 2 is an enlarged perspective view of the shelf removed; and Figs. 3, 4, 5, 6 and 7 are enlarged details.

In the drawings the numeral 2 designates a 35 portion of a suitable case formed of sheet metal of proper gage and adapted to receive a number of shelves. The shelves are composed of a skeleton frame work made up of bars of suitable thickness and said frames 40 comprise the front cross bar 4, the rear bar 5, the outer front-to-rear bars 6 and the inner front-to-rear bars 7. The outer front-to-rear bars 6 have at their inner ends the downwardly projecting hook or end portions 8 45 which are adapted to enter openings 9 in the rear wall of the case 2. In this way the inner end of the shelf is supported, while the shelf is supported at the outer end by the front cross-bars 4 which have the extensions 10 50 with the inwardly projecting ends 11 having openings 12 which receive the screws 13 adapted to secure the front cross-bars to the sides of the case 2. In this manner the shelf is held securely in position and owing to the 55 hooked inner end portions of the outer front-

to-rear bars which engage the openings 9 of the case there is no liability of the rear plate of the case being bulged or pushed outward by the force of the book shoved onto the shelf, and consequently no liability of the dropping 60 or falling of the shelf due to such action.

The rear cross-bar 5 is provided with hook portions 14 which are adapted to enter the openings 15 in the outer front-to-rear bars, the hook portions being readily insertible 65 within the openings 15 in assembling the shelf.

The inner front-to-rear bars 7 have hook portions 16 which are adapted to enter openings 17 in the rear cross-bar 5 in the same 70 manner. Intermediate cross-bars 18 connect the outer and inner front-to-rear bars 6 and 7, said intermediate bars having hook portions 19 adapted to enter openings 20 in the front to rear bars. 75

Toward the front of the shelf is the cross-bar 21 which has hook portions 22 adapted to engage openings 23 in the inner front-to-rear bars 7.

The front cross-bar 4 has formed in it the 80 notches 24 and on one side of each notch is the teat 25 and on the other side of the notch the seat or depression 26. These notches are formed at intervals to receive the outer ends of the front-to-rear bars 6 and 7, and said 85 front-to-rear bars are provided with notches 27. Just above the notches 27 in the bars 6 and 7 on one side thereof are the seats or depressions 28 and on the opposite sides of said bars are the projections 29. The projection 29 may be formed by the formation 90 of the depression in the opposite side of the bar, said bar being stamped with a suitable tool which will form the depression and at the same time cause the metal to protrude 95 slightly on the opposite side to form the projection 29. The notches 27 of the front-to-rear bars 6 and 7 are deeper than the notches 24 of the front cross-bar.

In assembling the parts of the shelf the 100 bars are first japanned as well as the rollers 30. The bars with the hook portions are inserted in corresponding openings while the rollers 30 are also inserted in the openings formed for them in the front-to-rear bars. 105 The parts are readily put together in this way and the last parts to be connected are the front-to-rear bars with the front cross-bar 4. The parts having been assembled in the way described the notches of the front 110

cross-bar and the notches of the front-to-rear bars will coincide so that by a blow administered to the front-to-rear bars the said bars will be forced down into engagement with 5 the front cross-bar. The notches of the front-to-rear bars will pass down and receive that portion of the front bar in line with the notches 24 formed in said front bar and at the same time the teat 25 will enter the seat 10 or depression 26 in the front-to-rear cross-bar while the projection 29 on the front-to-rear bar will enter the seat or recess 26 in the notch 24. The upper edges of the front-to-rear bars will be flush with the upper edge of 15 the front cross-bar and a very tight, secure joint is obtained which is not liable to work loose and consequently a strong, rigid shelf is provided with all the parts held firmly together without the employment of rivets. 20 As the only hammering required to connect the parts is that required at the last to unite the outer ends of the front-to-rear bars with the front cross-bar, which can be done with one blow, there is no liability of the distortion 25 or throwing of the frame out of true by the connecting of the several parts. Where the parts are connected together by rivets more or less bending or distortion of the bars occur. Furthermore, the rollers had to 30 be japanned separately and inserted after the frame had been assembled. This necessitated the bending of the bars somewhat to insert the rollers. By our invention, however, all this is obviated as the parts may 35 be japanned separately and assembled, together with the rollers, without any undue hammering or bending of the metal which would in any way tend to mar the finish.

The front cross bar is provided with the re- 40 entrant band 31 which provides means for the insertion of the hand to grasp the book in withdrawing same from the shelf.

It is apparent that the arrangement of 45 the rolls and other parts may be varied to suit conditions and we wish to include within our invention any such modified forms of construction.

What we claim is:

1. A roller book shelf comprising a skele- 50 ton frame composed of interlocking bars and rollers journaled therein.
2. A roller book shelf comprising a skele-

ton frame composed of bars, said bars being notched to engage each other, and rollers journaled in said bars. 55

3. A roller book shelf comprising a skeleton frame composed of bars, said bars being notched to engage each other and a teat in one notch adapted to engage a seat formed in the other bar. 60

4. A roller book shelf comprising a skeleton frame composed of bars, said bars being notched to engage each other, and a teat on one bar adapted to engage a seat in the notch of the other bar. 65

5. A roller book shelf comprising a skeleton frame composed of bars, said bars being notched to engage each other, a teat in the notch of one bar adapted to engage a seat formed in the other bar, and vice versa. 70

6. A roller book shelf comprising a skeleton frame composed of bars and rollers journaled therein, said bars being notched to engage each other, the notch in one bar being deeper than the notch in the other bar, 75 whereby the upper edges of said bars are flush with each other.

7. A roller book shelf comprising a skeleton frame composed of bars, hook portions on some of said bars engaging openings in 80 other bars, the front cross bar having notches formed therein, the front-to-rear bars having notches formed therein, whereby said front bar and front-to-rear bars are connected together. 85

8. A roller book shelf comprising a skeleton frame composed of a rear cross-bar having hook end portions, front-to-rear bars having openings therein adapted to be engaged by said hook end portions, a front 90 cross-bar having notches formed therein, and notches formed in the outer ends of said front-to-rear bars, whereby said front cross-bar and front-to-rear bars are connected together. 95

In testimony whereof, we the said THOMAS CARL PETERSEN and ERIK A. EKEDAHL have hereunto set our hands.

THOMAS C. PETERSEN.
ERIK A. EKEDAHL.
